UNITED STATES PATENT OFFICE.

DELMAR G. ROOS, OF BRIDGEPORT, CONNECTICUT, ASSIGNOR TO THE LOCOMOBILE COMPANY OF AMERICA, OF NEW YORK, N. Y., A CORPORATION OF WEST VIRGINIA.

JACK.

1,324,851.

Specification of Letters Patent. Patented Dec. 16, 1919.

Application filed July 17, 1916. Serial No. 109,626.

To all whom it may concern:

Be it known that I, DELMAR G. Roos, a citizen of the United States, and resident of Bridgeport, in the county of Fairfield and 5 State of Connecticut, have invented an Improvement in Jacks, of which the following description, in connection with the accompanying drawings, is a specification, like characters on the drawings representing 10 like parts.

This invention relates to lifting jacks, and among other objects aims to provide a simple and effective construction in which the lifting screw is operated by a motor.

15 The character of the invention may be best understood by reference to the following description of an illustrative embodiment thereof shown in the accompanying drawings, wherein:—

20 Figure 1 is a side elevation of an illustrative lifting jack shown herein as embodying the invention;

Fig. 2 is a vertical section through the jack shown in Fig. 1;

25 Fig. 3 is a horizontal section taken on line 3—3 of Fig. 2;

Fig. 4 is a vertical section taken on line 4—4 of Fig. 3;

30 Fig. 5 is a plan view of the switch member;

Fig. 6 is a section on line 6—6 of Fig. 5; and

35 Figs. 7 and 8 are wiring diagrams showing electrical connections for controlling the motor and brake, and illustrating the action of the switch.

Referring to the drawings, the illustrative lifting jack shown therein as embodying the invention comprises a base 1 (Figs. 1 and 40 2) on which is mounted and secured a casting 3 formed to present a motor receiving shell or socket 5, a hollow standard 7 and a handle 9.

45 In said standard is an elongated sleeve or nut 11 free to slide vertically, but confined against rotative movement by the rectangular shape of the interior of said standard. The upper end of said sleeve is formed to present a head 15 which may serve to engage the thing to be lifted. A screw 17 is threaded into said sleeve and when rotated will lift or lower the sleeve according to the direction in which said screw is turned.

An important feature of the invention re-

lates to a motor mechanism for rotating 55 said screw. To accomplish this said screw has a lower reduced end 19 keyed to the hub of a large gear 21 and preferably projecting somewhat beyond the lower face of said gear into a bearing 23. The lifting thrust 60 of the screw reacts through the hub of the gear to the base 1 where a ball bearing 25 is provided to reduce the friction between them.

The large gear 21 is driven by a pinion 27 65 formed on a stud shaft 29 depending from a spider 31 and journaled in a bearing 33 in the base 1 and a bearing 35 formed in a lining 37 within and fast to the motor shell 5 referred to. The spider 31 has stud shafts 70 39 projecting upward therefrom on which are journaled planetary pinions 41 meshing with an internal gear 43 formed on the inner surface of said lining. The planetary pinions 41 are driven by a sun gear 45 on 75 the rotor, herein the armature shaft 47, of an electric motor 49. The lower end of this motor rests on the upper edge of the lining 37 and may be clamped into said shell. To accomplish this the shell is split and formed 80 to present opposed ears 51 (Figs. 2 and 3), one tapped and both bored to receive a screw 53. By tightening said screw, the shell can be drawn securely to embrace said motor and hold the same in position. When 85 it is desired to remove said motor for purposes of replacement or repair, it is simply necessary to release said screw, and then the motor, together with its sun gear, may be lifted out of said shell. 90

Next will be described means for controlling the starting, stopping and direction of rotation of said motor. To accomplish this there is preferably provided a switch device such as that shown in detail in Figs. 5 and 95 6. This switch is adapted to be held in the hand and may be connected to the jack by any desired length of conductor, as indicated in Fig. 1. The switch as shown in Figs. 5 and 6 comprises opposed cup shaped members 55 and 57 fitting one within the other and connected by the smooth bolt 59 and nut 61 so that one may rotate relatively to the other.

The cup member 55 contains rubber or 105 other insulation material 65 in which are embedded fixed terminals, and the member 57 contains rubber or other insulation ma-

terial 67 recessed to receive bridge contacts for making and breaking the electrical connections between said terminals as more fully hereinafter described.

- 5 Referring to Fig. 7, the motor may be operated from any suitable source of electricity typified herein as a battery 69. In the installation shown the battery is connected by wire *a* with the terminal 71 which may 10 be connected by the bridge contact 73 with terminal 75. The terminal 75 is connected by the wire *b* with the field winding 77 of the motor which is in turn connected by the wire *c* with the terminal 79. The terminal 15 79 is connected by the contact 81 with the terminal 83 from which the wire *d* leads to the armature 85. From the armature 85 the wires *e* and *f* successively lead to the terminal 87 connected by the contact 89 to terminal 91 from which the wire *g* returns to the battery. Connected in parallel with the wire *f* by means hereinafter more fully described is a wire *h* leading to the terminal 93. 20
- 25 The electrical connections described are adapted to cause the current to flow in opposite directions through the motor armature to change the direction of rotation thereof according to whether the lifting 30 sleeve is to be elevated or lowered. When the switch is in the position shown in Fig. 7, the current passes from the battery through the wire *a*, the switch 71, bridge contact 73, the terminal 75. It passes thence 35 through wire *b*, field coil 77, wire *c*, terminal 79, bridge contact 81, terminal 83, wire *d*, the motor armature 85 and thence through the wire *f*, terminal 87, bridge contact 89, terminal 91, wire *g* back to the battery. 40
- 45 After the switch member 57 is turned in a clockwise direction to its position shown in Fig. 8, it will cause the bridge contact 73 to separate from the terminal 75 and connect the terminals 71 and 93, cause the bridge contact 81 to separate from the terminal 79 and to connect the terminals 83 and 75, and the bridge contact 89 to separate from terminal 87 and connect terminals 91 and 79. Now the current will pass 50 from the battery through the wire *a*, terminal 71, contact 73, terminal 93, wires *h* and *e* to the armature 85. Hence it passes through the wire *d* to the terminal 83, through bridge contact 81 to terminal 75, 55 thence through the wire *b* to the motor field coil 77 and through the wire *c*, terminal 79, contact 89, terminal 91 and wire *g* back to the battery. It is evident from the diagrams in Figs. 7 and 8 wherein the direction 60 of the current is indicated by arrows that shifting the switch reverses the current in the armature 85 and therefore reverses the motor. Stoppage or reversal of the motor may take place at any point in the travel 65 of the screw 17.

The motor may be controlled by the manually operated switch member and means are also provided whereby the motor is stopped as the lifting sleeve approaches either its upper or lower limit. In order 70 to give an understanding of the mechanism which accomplishes this, the connections of the wires *f* and *h* previously referred to will first be described. Referring more particularly to Figs. 2, 3 and 4, it will 75 be seen that these wires lead from contactors 95 and 97 mounted on an insulating member 99 on the side of the jack and spaced for a distance corresponding substantially to the normal travel of the sleeve. 80 The wire *e* is connected to a bus-bar 101 fastened to the contactors 95 and 97 by means of insulated bolts 103, best shown in Fig. 4. As the connections of the wires *h* and *f* are substantially similar, a description of the 85 upper one shown in Fig. 4 will suffice. The terminal 95 may be put into electrical communication with the bus-bar 101 by means of a switch 105 in the form of a lever pivoted on the insulated pin 107 and normally 90 held in contact with parts 95 and 101 by the spring 109. The switch for the wire *h* is the same as that for the wire *f* but is reversed in position swinging downwardly instead of upwardly when removed from the 95 parts 97 and 101. As is apparent from the description already given of the connections of the motor the current, when the head 15 is being raised, passes through the upper switch 105 and the wire *f* and when it is 100 being lowered through the lower switch and the wire *h*. The automatic stoppage of the motor is affected through these switches 105 as follows:

The lifting sleeve 11 carries a pin 111 provided with an insulating bushing 113 and projecting through the elongated slot 115 (Fig. 1) in the standard 7. As clearly shown in Fig. 1, the switch levers 105 cross the ends of this slot in the path of the pin 110 111. It is apparent that as the sleeve 11 is raised the pin 111 will travel upwardly in the slot 115 and as the sleeve reaches the upward limit of its travel will strike the upper switch 105 throwing it clear of the bus-bar 101 and contactor 95, thus breaking the circuit to the wire *f* and stopping the motor. When the motor is reversed and the sleeve descends the spring 109 will return the switch 105 to its place. Also when the 120 sleeve reaches the lower limit of its travel the pin 111 will throw the lower switch 105 breaking the circuit to the wire *h* in an exactly similar manner.

The switch levers 105 are made quite long 125 and the pin 111 is arranged to strike the same quite near their pivots. By such a design of the parts the action of the pin 111 in moving slowly against the switch levers 105 is multiplied in a large ratio so that 130

the contact is very quickly broken between the switch levers 105, the contactors 95 and 97 and the bus-bar 101.

To insure the prompt arrest of the motor, 5 a brake mechanism is provided. To this end the motor shaft 113 is continued upward somewhat above the motor to receive a brake disk 116 preferably conical in form. Coöperating with said disk is a brake shoe 117 10 normally urged into engagement with said disk by a helical spring 119 confined between said shoe and a cap 121 mounted on and secured to the motor. To prevent rotation of said brake shoe relatively to said casing, the shoe is notched to receive lugs 123 15 fast on the inner face of said casing.

To release said shoe from said disk, there is provided a solenoid 125 encircling said shoe, the latter being formed to serve as a 20 core entered centrally in the solenoid coil. When the coil is energized the shoe is drawn upward against the resistance of the spring 119 away from the disk.

The coil should be energized to withdraw 25 the shoe from the disk when it is desired to rotate the motor. To accomplish this the coil is bridged across the motor armature 77 by the wires *m* and *n*. By this arrangement the coil will be energized whenever the current flows in either direction through the 30 armature. When, however, the main switch is moved to neutral position to stop the motor or when either of switches 105 is opened the coil will be deenergized and the spring 35 will become effective to apply the shoe to the brake disk.

By my invention there is provided an efficient motor-actuated lifting jack having many advantages. The train of gears including the planetary gears provides a desirable speed reduction from the motor to the screw which enables heavy loads to be lifted with a small power motor. The casing completely incloses the gear transmission and 45 may be filled with lubricating material to maintain a continuous easy operation of the gear mechanism. The casing in completely inclosing the gear mechanism protects the same from dirt and other foreign matters 50 which, if admitted, would be likely to cause objectionable wear and injuries to the mechanism. The transmission mechanism is compactly arranged, thereby permitting the same to be incased in a small casing, reducing 55 the bulk of the jack as a whole and contributing to the lightness and ease of manipulation thereof.

It should be understood that the particular mechanism shown in the drawings is

merely one embodiment selected to illustrate 60 the invention, and that extensive deviations may be made therefrom without departing from the spirit and scope of the claims.

What I claim as new and desire to secure by Letters Patent is:—

1. In a lifting jack a base, a standard rising therefrom, a lifting member movable in said standard, a socket on said base having clamping means associated therewith, a transmission train extending from said lifting member and having an element within said socket and a motor fitting said socket and clamped thereto and having a rotor engaging said element.

2. The construction defined in claim 1 75 wherein the element comprises planet gears and the rotor is the sun thereof.

3. In a lifting jack a base, a standard rising therefrom, a lifting member movable in said standard, a socket in said base, a transmission train for said member housed in said base and having a driven element presented within said socket, an electric motor having a casing fitting said socket and a rotor projecting into driving engagement with said element, a cap on the opposite end of said casing, a brake shoe in said cap coöperating with the rotor and means controlled by the motor circuit for operating the shoe.

4. In combination, a lifting jack comprising a standard and a lifting member vertically movable therein, an electric motor for operating said member, an automatic brake associated with said motor and effective on stopping thereof, and means for interrupting the current to the motor when the member reaches predetermined positions of elevation and depression.

5. In combination, a lifting jack comprising a standard and a lifting member vertically movable therein, an electric motor for operating said member, an automatic brake associated with said motor and effective on stopping thereof, means for controlling the direction of rotation of the motor and means for interrupting the current to the motor when the member reaches predetermined positions of elevation and depression said means acting to place the motor in readiness for reversals.

In testimony whereof I have signed my name to this specification in the presence of two subscribing witnesses.

DELMAR G. ROOS.
